UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION.

LOOSE-LEAF LEDGER.

Application filed April 23, 1921. Serial No. 463,954.

To all whom it may concern:

Be it known that I, JOHN SCHADE, a citizen of the United States, residing at the city of Holyoke, in the county of Hampden 5 and State of Massachusetts, have invented certain new and useful Improvements in Loose-Leaf Ledgers; and I do declare the following to be a full, clear, and exact description of the invention, such as will 10 enable others skilled in the art to which it appertains to make and use the same.

This invention relates to certain new and useful improvements in loose leaf ledgers and the primary object thereof is to provide 15 novel sheet holding means for cooperation with sheets possessed of marginal U-shaped openings and more especially aims to provide holding means which includes a loose post which can be adjusted as to its length 20 according to the thickness of the mass of sheets and which is passed through circular openings formed in the sheets and removably engaged at its ends with the respective ledger sections.

25 A further object of the invention is to provide locking means for the sections which is alined with the row of posts that engage in the marginal openings so as to bind the sheets as far forward as possible 30 and thereby prevent relative spreading of the parts of the sections which are held rigidly when the ledger is locked to prevent removal of the sheets.

The invention also aims to provide novel 35 means for actuating the lock so as to dispense with the necessity of use of a key and therewith the rotating part actuated by the key.

Still further the invention aims to provide 40 a structure having improved means for anchoring the female members of the automatic extensible posts and of the clutch to the cheek pieces of the sections, and to also provide a structure wherein there are two posts carried by one section and one by 45 the other, the said other section carrying the female member of a locking means, so that upon separation of the sections, the removable adjustable post can be applied to the female member to constitute an extension thereof, whereby said other section 50 is thus equipped when separated with two sheet-holding posts, the same as in the instance of the first named section, so as to thus have each section similarly equipped 55 with sheet-engaging posts.

In the drawings:

Figure 1 is a top plan view of Figure 2;

Figure 2 is a fragmentary side elevation;

Figure 3 is a section on line 3—3 of Figure 4;

60

Figure 4 is an end elevation partly broken away and in section;

Figure 5 is a bottom plan view of the Figure 4;

Figure 6 is a section on line 6—6 of Figure 4;

65

Figure 7 is a longitudinal sectional view of the loose sheet holding post;

Figure 8 is a section on line 8—8 of Figure 7;

70

Figure 9 is a detail plan view of the lock operating slide;

Figure 10 is a section on line 10—10 of Figure 6;

Figure 11 is a section on line 11—11 of Figure 4, and

75

Figure 12 is a fragmentary view of a sheet with the holes therein.

In proceeding in accordance with the present invention, cheek pieces 1 and 2 are 80 employed having overlapping tongues 3 and 4 as shown in the drawings. The cheek pieces are formed hollow so as to constitute housings and are provided with openings to loosely receive the ends of an adjustable sheet-holding post which latter as shown in Figure 7 consists of the telescopic sections 5 and 6. Section 6 has a long screw 7 therein spaced from its inner surface, while section 5 has a bifurcated and internally threaded thickened head 8 which engages the threads of the screw 7 and is held at its periphery by frictional engagement with the inner circumference of the section 6 into threaded engagement with the screw 90 7 thereby obviating threading of the section 5 throughout its length. In this manner by relative turning of the sections 5 and 6 the length of the post may be varied as desired, and the latter dropped through the circular 95 holes H of the sheets S as shown in Figure 12.

In the present invention automatically operating spring posts are employed as set forth and claimed in an application filed 105 April 2, 1921, Serial No. 458,014, the posts having female members 9 and male members 10. One of the automatic posts is carried by one of the sections 1 and two by the other section 2 and the section carrying the 110

said one post also carries a female member 11 similar to the female members 9 of the automatic posts, the member 11 being utilized as the female member of the clutch. This 5 member 11 is aligned with the automatic posts and receives the male member 12 of the clutch. The clutch proper is of the friction type and is generally designated 13 and forms the subject matter of a companion 10 application filed April 2, 1921, Serial No. 458,015.

The present invention aims to provide improved means for anchoring the female members 9 and 11 to the respective cheek pieces, so as to give same lateral support throughout their entire circumference and accordingly these members have laterally extended flanges 14 which are spot-welded to tongues 3 or 4 of the cheek pieces. As 15 shown in Figures 4 and 11, the flanges 14 of the female member 9 attached to the lower binder member are each spot-welded to a plate 15 which is of a length indicated by dotted lines in Figure 4, which spaces 20 the flanges 14 from the tongue 4 so that the tongues can telescope, the tongue 3 being provided with the cut-outs 16 to receive the plates 15 as depicted in Figure 4. The ends 25 of the female members are eyeletted or expanded as shown at 17 in Figure 6 to secure them in openings in the cheek pieces 1 and 2.

The formation and securement of the female members greatly strengthens the latter since they are thus firmly supported 30 throughout their length. Further they are not only reenforced by the eyeletting 17 at their base ends, but also by the spot-welded side or lateral flanges, this additionally strengthening the angle formed by the 35 tongues and the cheek pieces preventing distortion of such angle.

For the purpose of operating the clutch into and out of clutching positions, the male member 12 (Figure 6) is threaded at its 40 base end into engagement with a plate 18, the latter being disposed in the space between a pair of ears 19, which are carried by the housing 20 of the male member 12 of the clutch. A pin 21 extends through the ears 45 19 so as to be supported thereby, and is constantly urged upwardly by the end of a leaf spring 22, the latter being held in position by a screw 23 (Figure 4) which screw also holds the plate 18 in rigid connection with 50 the cheek piece 2. As illustrated in Figure 9, a forked member 24 is employed to actuate the housing member 20, the arms of which member 24 are tapered at 25 and engage between the ends of the pin 21 and the 55 base 26 of the tongue 4, the base 26 forming a part of the cheek piece or housing 2 as Figure 6 illustrates. The forked member 24 is provided with a thumb piece 27 extending through a slot 28, formed in a depressed or concaved part 29 in the outer side 60 65

of the cheek piece or housing 2, shown clearly in Figures 4 and 5 of the drawing.

From the foregoing it will be seen that in order to move the clutch to clutching and unclutching positions, it is merely necessary 70 to move the slide member 24 by engagement with its thumb piece 27, thereby moving the housing 20 of the clutch to render the latter operative or inoperative, the spring 21, normally acting to hold the clutch operative. 75

As shown in Figure 3 of the drawings the spring 30 of one of the automatic posts overlies the forked slide 24 and in order to support the lower end of this spring, a knob 31 is employed reduced to receive the spring 80 and having its outer end rounded so as to engage the slide 24 in a manner to not interfere with free movements of the slide, as shown in Figure 3.

When the ledger sections are separated 85 and placed on a stand (not shown) for the purpose of transferring the leaves from one section to another, the manually adjustable removable post composed of the parts 5 and 6, is removed and its smaller end dropped 90 into the female member 11 of the friction clutch, which affords an extension post for use when the leaves are transferred. It will be observed that one of the ledger sections has two automatically operating extension posts while the other has only one, which is due to the fact that the invention 95 supplants one post by the friction clutch, and the female member of this post is required to perform two functions, namely, 100 a member of the clutch and also an extension post when the clutch member 20 is removed and member 5 of the sheet-holding post is inserted therein as above noted.

After the sheets-holding post has been inserted through the circular perforation H in the sheets, and seated within one cheek piece, the outer end thereof should project beyond the mass of sheets not over a quarter of an inch so that the post will not be so long as to interfere with the proper closing 110 of the ledger sections, and when the latter are closed this outer end of the post will seat within a corresponding socket in the other cheek piece. 115

The sheet-holding post is used when the ledger sections are separated and placed upon the stand since one section carries the two resilient extension posts while the other section carries only the single resilient extension post and the housing which 120 operates as the female member of the clutch. Now when these sections have been separated there will be only one long post on the said other section, and although the female member of the clutch acts as the other post it will be too short, when the accountant transfers the leaves from one section to the other section, and accordingly 125 the manually adjusted post heretofore re- 130

ferred to is pulled out of the mass of leaves held by the first section and one end inserted within the female clutch member so as to thus provide an extension post. When 5 the leaves have been transferred from the second to the first section the accountant merely sees that when the sheet holding post is returned to its normal position in the leaf perforations the extreme outer end of 10 this manually adjusted post is so manipulated that it will project up above the leaves not over a quarter of an inch and the ledger sections are then closed.

What is claimed is:

- 15 1. A ledger binder composed of two separable sections and resiliently extensible post members permanently carried by each of said sections for engagement within edge apertures in the loose sheets, and an extensible post comprising manually adjustable sections removably engageable with said binder sections and extending within perforations in said sheets to secure them as against removal.
- 25 2. In a loose leaf ledger, a pair of separable sections, hollow telescoping posts that are secured respectively at one end to opposite sections and are entirely free at the other end for engagement in edge openings in the sheets, a coil spring within these posts whereby the latter are automatically extensible or contractible, and a loose post composed of two threadedly connected sections formed to engage through circular 30 perforations in the sheets to hold the latter against removal.
- 35 3. A loose leaf ledger comprising a pair of separable sections, containing sheets having circular holes and edge slots, a pair of automatically extensible posts carried by one section, an automatic extensible post carried by the other section, locking means for the sections including a female member carried by said other section, and a sheet-holding post formed to loosely engage the respective sections at its ends and formed to engage through the circular holes of the sheets, said sheet-holding post being so constructed as to be received in the female member of the locking means so as to constitute an extension thereof when the sections are separated.
- 50 4. In a loose leaf ledger, a pair of sepa-

rable binder sections, automatically operating telescoping locking means for the sections, and automatically extensible posts that are respectively secured at one end to opposite sections the other ends being entirely free, said posts including female members having opposed flanges along their sides secured to the sections.

5. In a loose leaf ledger, a pair of separable sections, and locking means therefor including a clutch having a slideable member, a spring for tensioning said member, and a slide having a thumb piece said slide being adapted to engage said member to move same against the action of the spring to unclutched position.

6. In a loose leaf ledger, a pair of separable sections, posts carried by each section, and locking means for the sections composed of telescopic clutch members, ears carried by one of the clutch members, a pin carried by the ears and having its ends extending therebeyond, a leaf spring engaged with the pin beneath the latter and arranged between the ears, and a forked slide having tapered ends disposed outside of the ears and carrying the pin ends to actuate 70 said clutch member.

7. In a loose leaf ledger, a pair of separable sections and automatically extensible posts carried by the sections and composed of telescopic male and female members that are respectively secured at one end to opposite sections and are entirely free at the other end, the female members having opposed lateral flanges along their sides spot-welded to the sections.

8. In a loose leaf ledger, a pair of separable sections and automatically extensible posts carried by the sections and composed of telescopic male and female members that are secured respectively at one end to opposite sections and are entirely free at the other end, the female members having opposed lateral flanges along their sides, and means to secure the flanges of each female member to the section which carries said member, whereby the male and female members will be aligned for telescopic engagement.

In testimony whereof I affix my signature hereto.

JOHN SCHADE.
